[57] CLAIM

The ornamental design for a standing holder for tumbler and toothbrushes, as shown and described.

DESCRIPTION

FIG. 1 is a perspective view of a standing holder for tumbler and toothbrushes, showing our new design;

FIG. 2 is a top plan view thereof;

FIG. 3 is a front elevational view thereof; and

FIG. 4 is a left side elevational view thereof, taken looking from the left of FIGS. 2 and 3, the right side elevational view, which is not shown, being a mirror image of this FIG. 4.

The shading in the views is intended to represent a metallic reflective surface on the lower section of the holder as contrasted with the transparent surface for the remainder of the holder.
